CLAIM

The ornamental design for a disposable filter holder, as shown and described.

DESCRIPTION

FIG. 1 is a top plan view of a disposable filter holder showing my new design;

FIG. 2 is a bottom plan view thereof;

FIG. 3 is a right side elevation view thereof;

FIG. 4 is a left side elevation view thereof;

FIG. 5 is an end elevation view thereof, the opposite end being substantially a mirror image of that shown; and

FIG. 6 is a cross-sectional view thereof taken along line 6—6 in FIG. 1.
